US0D1068719S

(12) **United States Design Patent** (10) **Patent No.:** **US D1,068,719 S**
(45) **Date of Patent:** **** Apr. 1, 2025**

(54) **COMBINED FRIDGE MAGNET AND SPEAKER**

(71) Applicant: **Guangzhou Yaoluoyue Technology Co., Ltd**, Guangdong (CN)

(72) Inventor: **Wei Chen**, Guangdong (CN)

(73) Assignee: **Guangzhou Yaoluoyue Technology Co., Ltd**, Guangzhou (CN)

(**) Term: **15 Years**

(21) Appl. No.: **29/972,406**

(22) Filed: **Nov. 10, 2024**

(51) **LOC (15) Cl.** **14-01**

(52) **U.S. Cl.**

USPC **D14/172**

(57) **CLAIM**

The ornamental design for a combined fridge magnet and speaker as shown and described.

DESCRIPTION

FIG. 1 is a perspective view of a combined fridge magnet and speaker showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the combined fridge magnet and speaker and form no part of the claimed design.

1 Claim, 8 Drawing Sheets
